ILLUMINABLE CLIP BOARD

George J. Cory, 11722 Archwood Ave.,
North Hollywood, Calif.

Filed Mar. 7, 1960, Ser. No. 59,631

Term of patent 14 years

(Cl. D74—2)

FIG. 1

FIG. 2

FIG. 3

FIG. 4

FIG. 5

FIG. 1 is a top perspective view of an illuminable clip board showing my new design;

FIG. 2 is a left side edge elevational view thereof;

FIG. 3 is a right side edge elevational view thereof;

FIG. 4 is a rear elevational view and;

FIG. 5 is a bottom view thereof.

The broken line illustration of the watch in FIG. 1 is for illustrative purposes only.

I claim:

The ornamental design for an illuminable clip board, as shown and described.
